REPEAT CYCLE TIMERS

Paul A. Hagen, Baraboo, Wis., assignor, by mesne assignments, to The Gamewell Company, Newton, Mass., a corporation of Delaware

Filed Jan. 14, 1959, Ser. No. 786,747

12 Claims. (Cl. 307—141.4)

The invention relates to a functionally and structurally improved and simplified timer that will repeat a selected time cycle, each cycle comprising an interval during which one or more switches are closed and a second, shorter interval during which the switch or switches are open. A second set of switches may be arranged to operate in the reverse order.

The invention is believed to be novel in that the load controlling and timer motor controlling switch is moved between a fixed and an adjustable stop.

Another novel feature of the invention is its self-adjusting reset spring: as the timing interval is lengthened and the distance the switch must travel during reset is increased, the reset spring is wound tighter and its initial torque is thereby increased. The increased torque returns the switch at a faster rate at the longer time settings. Thus, reset time tends to be constant over a range of timing intervals. For shorter intervals the initial torque of the reset spring is lowered; for longer intervals the initial torque of the reset spring is increased. The characteristics of the spring can be chosen so that the variation in the initial torque will cause the reset time to be approximately constant for any selected time setting.

In a modified form of the invention, the outer end of the reset spring is fixed. As the distance the switch must travel during reset is increased with an increased setting on the dial, the spring torque is greater at the end of a short reset interval than at the end of a long reset interval. This tends to make the duration of the reset interval proportional to the timed interval. The spring tension is identical at the beginning of all reset intervals, regardless of timing duration, but at the end of a long distance reset interval the spring is unwound more and the tension is less. The average reset torque decreases as the timed interval (and the reset distance) increases; thus causing the reset time to be greater when the timed interval is greater. If the spring characteristics are properly selected the reset interval will be proportional to the timed interval.

The preferred form of the invention employs the increasing torque feature. As the timer is set to time a longer interval and the distance the switch travels during reset is necessarily increased, the torque of the reset spring is also increased. When the timer is set to time a shorter interval, thereby decreasing the distance the switch travels during both the timing interval and the reset interval, the torque of the reset spring is also decreased. This tends to make the reset interval constant for various settings of the timer dial. Spring tension is always the same at the end of the reset rotation, regardless of timer dial setting.

The modified form of the invention employs the proportional timing feature. That is, the duration of the reset interval is proportional to the duration of the timed interval at all settings of the timer dial. At the beginning of the reset interval the torque of the reset spring is always the same, regardless of timer dial setting.

The invention greatly simplifies presently known appa-

2

ratus by providing an instantaneous make and break switch in the circuits established or broken at the end of each timing interval. No external relay is required to boost the capacity of the timer contacts. In many timers, the time determining element moves at a fixed rate of speed over a fixed path and makes or breaks contacts at each end of the path. The present invention rotates a snap acting switch over an adjustable path; at the ends of the path the switch is actuated to provide rapid opening or closing of the circuit. Thus, arcing is not a problem.

Known timing devices usually employ cams, cam followers, and electric contacts to control a load device and the timer motor. The invention eliminates the cams and cam followers and utilizes a snap acting switch to control the external load device and the timer motor.

Known timers also employ a solenoid operated clutch mechanism to disengage the camshaft from the motor during reset as the motor has inertia that would prevent rapid reset if it were left engaged during reset. The present invention eliminates the solenoid and employs a simple clutch built into the standard motor.

The switching arrangement used in the invention is superior to known arrangements in its foolproof operation. The switch is of the reset type and is actuated at the end of its travel in either direction and remains in that condition until it is carried to the other operating point where it is again actuated. During travel in either direction there is nothing to cause it to switch accidentally.

Another desirable feature of the timer is that it may be reset during any portion of its timing cycle by momentarily opening the circuit to the motor. The timer resets itself and starts timing a fully timed interval as soon as power is restored. This feature is important when the device controlled by the timer must not be energized until a full interval has elapsed after power is restored after a power failure.

The timer switch may be connected to transmit a short pulse at the end of the timed interval. The duration of the short pulse is in one embodiment substantially constant for various timer settings and in another embodiment is proportional to the timed interval. In either form it corresponds to the full time required for the device to reset. The differences in resetting time are obtained in the first form by winding the reset spring tighter for the longer timing cycles, and in the second form by anchoring the reset spring to a fixed support.

The short pulse occurring at timed intervals is useful in a large number of timer applications. One application of the invention is in conjunction with a photographic slide changer projector in which the viewing interval is timed by the timer. At the end of the viewing interval the timer energizes the slide changer solenoid injecting a new slide and ejecting the viewed slide. The invention will be illustrated with respect to this use but is by no means restricted to this usage.

The invention will be described with the aid of the accompanying drawings in which

Figure 1 shows the invention, diagrammatically, in perspective.

Figure 1A shows one portion of the invention in a second form.

Figure 2 is a section taken along line 2—2 in Figure 1.

Figure 3 is a section taken along line 3—3 in Figure 1.

Figure 4 shows the timer circuit during the timing interval.

Figure 5 shows the timer circuit during the resetting interval.

Figure 6 is a diagram showing the timer circuit and a slide changer.

In the drawings, a synchronous motor 1 drives a pinion

2 through reducing gears (not shown) in gear box 3 which forms a part of motor housing 4. A unidirectional clutch arrangement 5 (not shown) is built into the gear box 3 and permits the motor to drive the main timer shaft 7 through the gear 6 keyed thereto. Shaft 7 cannot rotate the motor in the reverse direction because of the one-way clutch 5.

As the motor 1 drives the main timer shaft 7 in a counter clockwise direction, as viewed from the dial 13, the reset spring 10 is wound tighter. The inner end of spring 10 is anchored to shaft 7 and the outer end 11 of spring 10 is attached to movable stop 12. When power is removed from motor 1 reset spring 10 will rotate shaft 7 in a clockwise direction.

Main timer shaft 7 is thus driven in one direction at a slow rate of speed determined by the speed of motor 1, gear reduction 3, and the size of pinion 2 and reducing gear 6. Shaft 7 is driven in the opposite direction at a higher rate of speed determined by reset spring 10 and the friction and inertia of the rotating parts.

Affixed to timer shaft 7 is an L-shaped bracket 15 to which a snap acting switch 16 is affixed. As shaft 7 oscillates it carries with it bracket 15 and switch 16. Switch 16 is of the reset type and has an actuator 17 having both ends 17', 17" exposed. As the switch is rotated in either direction it moves until the ends 17', 17" of its actuator come in contact alternately with a fixed stop 18 or the movable stop 12. Gradual movement of actuator 17 causes additional stressing of the prestressed member within the switch 9 until the contacts snap into the reverse position. They remain in this position until actuated to the other position.

The time it takes motor 1 to rotate switch 16 from the movable stop 12 to the fixed stop 18 determines one period of the cycle; the time it takes reset spring 10 to return switch 16 from fixed stop 18 to movable stop 12 determines the second period of the cycle. The second period can be made almost constant regardless of the duration of the first period of the cycle because movable stop 12 winds reset spring 10 tighter as the settable timing period is increased. The additional torque of reset spring 10 resets switch 16 over a greater arc in approximately the same interval of time. When the first portion of the cycle is adjusted to be of short duration, movable stop 12 partially unwinds reset spring 10; the decreased torque resets switch 16 in approximately the same interval.

In a second form of the invention shown in Figure 1A the outer end 11 of spring 10 may be affixed to a post 19 permanently attached to a frame member. The torque of reset spring 10 thus does not vary as the interval is changed. The reset interval is thus substantially proportional to the settable interval.

The duration of the one period is preset by turning knob 8 to the graduation marked on dial 13 corresponding to the desired interval.

The dial 13 is calibrated in units of time corresponding to "on" time, and is linear. Various motor speeds are available to give a range of timing limits.

The timer is made to time repetitively by connecting motor 1 to a power source L1, L2 through the timer's own switch contacts, as shown in Figure 4. One line from the power source L2 is connected to the common terminal C of the timer switch 16. One motor lead 21 is connected to the normally closed contact terminal NC of the timer switch. The remaining motor lead 19 is connected to the L1 line of the power source. A circuit to the motor is thus established. The timed interval ensues while motor 1 rotates switch 16 counter clockwise until actuator 17' is brought up against fixed stop 18, Figure 1. The travel of actuator 17 stops but switch 16 continues in a CCW direction until the snap action of the switch opens the circuit between contact terminals C and NC, as shown in Figure 5. Motor 1 is thus deenergized and reset spring 10 quickly rotates

switch 16 in a CW direction. During this resetting interval power flows out on the normally open contact terminal NO to the load.

The resetting interval ensues while reset spring 10 rotates switch 16 in a CW direction until actuator end 17" is stopped by movable stop 12 and switch 16 continues until the snap action of the switch opens the load circuit and closes the motor circuit. The motor turns shaft 7 and switch 16 in a CCW direction and the cycle is repeated until power is removed.

The invention is illustrated in Figure 6 in conjunction with a photographic slide changer. As explained above one power line L2 is connected to the common switch terminal C. Motor lead 21 is connected to the normally closed contact terminal NC and receives power through the common contact arm from terminal C and line L2. A momentary type pushbutton switch 20 is connected in line 21 so that the circuit may be broken momentarily. Motor lead 19 is connected to line L1.

The slide changer shown in Figure 6 consists of a solenoid coil 22, a plunger 23, a return spring 24, a biased finger 25, a new slide 27 and a viewed slide 28. The solenoid coil 22 is connected as a load between the normally open contact NO and line L1. When power is applied at L1, L2, the motor is energized and timing commences. When motor 1 has moved switch 16 to fixed stop 18 and caused actuator 17' to be depressed, the action of switch 16 snaps the movable arm and contact into contact with the normally open contact NO. Power now flows from L2, through the movable arm and contact C, through normally open contact NO, and through the load device 22 to the L1 terminal.

Power flows in this external load circuit while the timer is resetting. Normally, the resetting interval is in the order of one second or less. During this time power energizes coil 22 of the slide changer causing the replacement of the viewed slide 28 with a new slide 27.

When the switch 16 has been rotated by reset spring 10 sufficiently to permit actuator 17" to be depressed against movable stop 12, the snap action of the switch 16 changes the position of the movable arm and contact to that shown in Figure 6. The external load circuit is deenergized and the magnetic attraction of coil 22 for plunger 23 decays allowing spring 24 to draw plunger 23 to the left thereby releasing finger 25 for movement of another slide when solenoid 22 is again energized. The movable arm and contact closes the NC circuit to motor 1 starting another timed interval.

The duration of the timed interval is readily adjusted by rotation of knob 8 over calibrated dial 13. Knob 8 is keyed to the short shaft 26 to which movable bracket and stop 12 are affixed. Setting may be made either while the timer is deenergized, timing, or resetting. Dial shaft 26 may be rotated independently of timing shaft 7. Dial shaft 26 is kept from rotating under action of the timer through friction washers 29, one washer being fixed against rotation.

The manually operated switch 20 provided in the motor control circuit 21 is normally closed and has no effect on timing. When switch 20 is opened, however, it removes L2 power from the motor 1, permitting the reset spring 10 to reset the timer to zero. Timing does not start again until the switch 20 is closed supplying L2 power to the motor. The switch 16 is not affected by this operation and the duration of the timed interval is increased.

In the application of the timer shown in Figure 6 the viewing time is set on the dial 13; at the end of each viewing interval an electric pulse of short duration is sent to the slide changer solenoid 22. The operation of the solenoid ejects the viewed slide 28 and injects a new slide 27. If additional viewing is desired, a momentary depression of switch 20 causes the timer to reset to zero. A full viewing interval will transpire before the solenoid 22 is again energized by the timer. The switch

16 is not reset when the timer motor is deenergized because the switch 16 must be driven against the fixed stop 18 in order to be reset. Otherwise, a pulse would occur when switch 20 is again closed and the slide would be ejected.

One novel feature of the interrupter is lack of a cam. The time setting is made from the front with the twist of a knob 8. Attached to the dial shaft 26 is the movable stop 12 whose angular displacement determines the time setting. Since timing is at a uniform rate, the scale of time setting shown on dial 13 is linear throughout its entire range.

Another novel feature of the invention is the movable switch 16. Rather than move a cam into the switch 16 as is general practice, the switch 16 is moved between stops. This is accomplished by affixing the snap-action switch device 16 to the timer shaft 7 and rotating it between stops 12 and 18. The actuator 17 is thereby moved between its two limiting positions 17', 17''. As the switch 16 oscillates between stops 12 and 18 it controls the electric load 22 in the manner desired. During its timed rotation it energizes the timing motor 1 and may energize an external electric circuit NC. Connection between the moving switch and a terminal block (not shown) is made with flexible leads.

Another novel feature of the invention is the constant or variable torque reset spring which permits the choice of a second timed portion of the cycle either proportional to the first or substantially constant.

I claim:

1. A repeat cycle timer, including a snap acting switch actuatable into either a conducting condition or a non-conducting condition, a timing motor energized through said switch when said switch is in said conducting condition and adapted to move said switch over a path of finite, adjustable length, a first stop located in the path of said switch and adapted to actuate said switch and thereby cause it to change its condition from one stable condition to another stable condition, a second stop located in the path of said switch and adapted to also actuate said switch and thereby cause it to change its condition from said other condition to said one condition, one of said stops movable to lengthen or shorten said path, said timing motor adapted to move said switch over said path in one direction, a prestressed return spring adapted to move said switch over said path in a return direction, said return spring connected to the adjustable one of said stops and adapted to be increasingly prestressed when said path is lengthened and to reduce the prestress of said spring when said path is shortened to thereby maintain the return time of said switch substantially constant.

2. In a repeat cycle timer, in combination, a resettable snap acting switch adapted to be oscillated over an adjustable length path, stops defining each end of the path, the snap switch reset from a conducting condition to a non-conducting condition at one end of said path and from a non-conducting condition to a conducting condition at the other end of said path, a timer motor energized through said switch and adapted to drive said switch at a timed rate when said switch is conducting, a reset spring adapted to drive said switch in a reverse direction when said switch is non-conducting and said motor is deenergized, said reset spring changeable as to tension as the length of said reset path is adjusted and a load circuit also controlled and timed by said switch.

3. A repetitive cycle timer having, in combination, a snap switch, said switch having an actuator projecting from two opposite sides of said switch, a shaft supporting said switch and adapted to rotate said switch through an arc, an adjustable abutment engaged by said switch actuator limiting rotation of said switch in one direction, a stop engaged by said switch actuator limiting rotation of said switch in the opposite direction, an electric circuit closed when said switch actuator engages said adjustable abutment, a synchronous motor energized through

said circuit, a speed reducer and a unidirectional clutch between said motor and said shaft adapted to drive said shaft at a uniform rate of speed in one direction, a reset spring having one end affixed to said shaft and another end affixed to said adjustable abutment and adapted to rotate said shaft in the reverse direction after said switch actuator engages said stop and opens said circuit, said switch alternately rotated by said motor and then by said reset spring into contact alternately with said stop and then with said adjustable abutment, this cycling repeated until power is removed, the duration of the reset time remaining substantially constant for various settings of said adjustable abutment, and a load circuit connected through said switch and controlled thereby.

15 4. In a cycle timer as in claim 3, an external circuit energized through said switch during its entire reset interval.

20 5. In a cycle timer as in claim 3, an external circuit energized through said switch during its entire motor driven interval.

25 6. In a repeat cycle timer, a plurality of spaced apart frame members, a unidirectional motor and reduction gear box mounted external to one frame member, a drive pinion mounted between the frame members and rotated by said motor and gearing, a unidirectional clutch between said gearing and said pinion, a drive shaft journaled in one of said frame members, a gear affixed to said shaft and meshing with said pinion, a reset spring coiled about said shaft and having its internal end affixed to said

30 shaft, a presetable rotatable bracket member frictionally journaled in one other of said frame members in axial alignment with said shaft and having one end adapted to hold the external end of said spring and upon rotation of said bracket member in one direction to stress said

35 spring additionally, a second bracket member affixed to said shaft and having at least one flat surface, a reset type snap acting switch affixed to said flat surface, said switch adapted to be rotated by said shaft in a plane normal to the axis of said shaft, said switch having a

40 two ended actuator, one end of said actuator movable against said presetable bracket and the other end of said actuator movable against a fixed stop, a fixed stop attached to one of said frame members, an electric circuit including a source of power and said switch and said

45 motor and adapted in one condition of said switch to energize said motor to thereby rotate said shaft and said switch at a constant speed between said presetable bracket and said fixed stop, and in another condition of said switch to deenergize said motor and to permit said

50 reset spring to rotate said switch between said fixed stop and said presetable bracket, the condition of said switch reversed when said actuator strikes said presetable bracket and again reversed when said actuator strikes said fixed stop, the time of travel between said fixed stop and said presetable bracket being substantially constant for all settings of said presetable bracket, and a load circuit through said switch energized during the entire time said switch travels between said fixed stop and said presetable bracket.

60 7. A cycle timer providing successive time cycles each of which comprises an adjustable interval and a substantially fixed reset interval, having in combination, a movable interval determining element, a fixed stop for said interval determining element, an adjustable stop, electric

65 motor driven means to move said element at a fixed speed from said adjustable stop to said fixed stop the time required determining the adjustable interval, means placing current on said motor when said element reaches said adjustable stop and taking off the current when said element reaches said fixed stop, a prestressed coil spring having one end attached to said element for returning said element from said fixed stop to said adjustable stop,

70 means connected to the other end of said spring to increase the prestress as the movable stop is rotated to increase said adjustable interval to thereby increase the

speed of return travel of said element as the distance between the stops is increased to thereby maintain the reset interval substantially constant.

8. In a cycle timer as in claim 3, said adjustable abutment rotatable about said shaft to lengthen or shorten the path traveled by said switch to thereby proportionally increase or decrease the duration of the portion of the cycle timed by said motor driving said switch.

9. In a cycle timer as in claim 3, a time cancelling circuit comprising a manually operable switch connected in circuit with said motor and adapted when opened during the time that said motor is energized to deenergize said motor and permit said reset spring to return said first named switch to said adjustable abutment without altering the condition of said first named switch, said manually operable switch when reclosed adapted to reenergize said motor to permit said motor to drive said first named switch the full length of its path and thus time a full interval.

10. A timer, including in combination, a resettable double throw snap acting switch structure having an actuator for urging the electric switch therein into two different conditions, a support, a unidirectional synchronous motor mounted on said support and having reduction gearing and a unidirectional clutch and an output pinion, a shaft journaled to said support and having a driven gear in mesh with said pinion and providing a support for said switch, a reset spring coiled about said shaft and having one end affixed to said shaft, a fixed stop attached to said support and having one portion in the path of said actuator on said switch when said switch is rotated by said motor, an adjustable stop frictionally attached to said support and having one portion movable into the path of said actuator on said switch, a second portion of said adjustable stop adapted to retain the outer end of said reset spring and to wind said spring additionally as said adjustable bracket is moved to lengthen the path of said switch and to unwind said spring as said adjustable bracket is moved to shorten the path of said switch, the reset time of said switch thereby maintained substantially constant regardless of length of path of said switch.

11. In a repeat cycle timer adapted to time a settable

interval and a reset interval substantially proportional thereto, in combination, a reset type snap action switch adapted to be oscillated over an adjustable length path, stops defining each end of the path, the length of said path proportional to the duration of the settable interval, said snap switch reset from a conducting to a non-conducting condition at one end of the path and from a non-conducting to a conducting condition at the other end of the path, a timer motor energized through said switch and connected to drive said switch at a timed rate from one to the other of said stops when said switch is conducting, a reset spring initially stressed to drive said switch in a reverse direction when said switch is non-conducting and said motor is deenergized, said reset spring prestress increased as said motor drives said switch over its path, and a load circuit controlled and timed by said switch.

12. In a repeat cycle timer, in combination, a resettable snap acting switch adapted to be oscillated over an adjustable length path, stops defining each end of the path, the snap switch reset from a conducting condition to a non-conducting condition at one end of said path and from a non-conducting condition to a conducting condition at the other end of said path, a timer motor energized through said switch and adapted to drive said switch along said path at a timed rate when said switch is conducting, a reset spring adapted to drive said switch in a reverse direction when said switch is non-conducting and said motor is deenergized, said reset spring adapted to be adjusted as to tension as the length of said reset path is adjusted, and a load circuit also controlled and timed by said switch.
